LEONARD F. BURCHETT

INVENTOR

BY
Richard B. Owen ATTORNEY.

UNITED STATES PATENT OFFICE.

LEONARD F. BURCHETT, OF EDMONTON, ALBERTA, CANADA.

RADIATOR.

Original application filed January 7, 1920, Serial No. 349,855. Divided and this application filed May 31, 1921. Serial No. 473,791.

To all whom it may concern:

Be it known that I, LEONARD F. BURCHETT, a citizen of the United States, residing at Edmonton, in the Province of Alberta and 5 Dominion of Canada, have invented certain new and useful Improvements in a Radiator, of which the following is a specification.

This invention relates to a radiator for heating purposes and has for its object to 10 generally improve upon radiators of this character by providing a device which will be of extremely simple, durable and inexpensive construction, one which is efficient and reliable in operation, and well adapted to 15 the purpose for which it is designed.

With the above and numerous other objects in view, the invention resides in certain novel features of construction, and the combination and arrangement of parts as will be 20 hereinafter fully described and claimed.

The subject matter of the present invention was divided from my pending application relating to a duplex humidity heating system filed January 7, 1920, Serial Number 25 349,855.

In the drawings:—

Figure 1 is a side view of the radiator, parts being broken away,

Figure 2 is an end view of the radiator, 30 an end portion being broken away, and

Figure 3 is a top plan view of the radiator, a portion of the top being broken away to show more clearly the formation of the body.

Referring to the drawings in detail it will 35 be seen that the radiator is constructed with a perforated top to admit of the ready escape of vapor whereby the atmosphere is rendered humid and the temperature regulated. As shown more clearly in Figures 2 and 3 the

40 top 1 is provided with a plurality of openings 2 which are distributed throughout the extent of the top and of such size as to provide a ready escape for steam. The body 3 of the radiator is fluted or corrugated to 45 provide heat radiating surface and to allow for contraction and expansion whereby in the event of the radiator freezing it will not

suffer fracture, or other injurious results tending to throw the radiator out of service. In the preferable construction the parts of 50 the radiator are formed of sheet metal pressed or otherwise fashioned into the desired shape. While it is preferred to construct the radiator of sheet metal wholly or in parts it is to be understood that it may be 55 cast in the usual way.

A heating pipe 5 is disposed within the lower portion of the radiator and is connected with the heating fluid supply pipe 6. The pipe 5 may be of any size and is connected at its ends with the ends of the radiator by suitable fittings. The end of the pipe remote from that connected with the supply pipe 6 is adapted to be closed by means of a plug or cap 7 which when removed admits of draining the radiator. A valve 8 is disposed in the connection between the supply pipe 6 and the radiator pipe 5.

At 9 in the pipe 5 there is provided an opening for receiving the smaller pipe 10 70 which is provided at its end with an air release valve 11 which is situated within the radiator.

The top 1 is provided with a pair of annular depending flanges 12 and 13. The 75 flange 12 is disposed within the flange 13 and extends at right angles from the body of the top 1 while the flange 13 extends at an obtuse angle therefrom. The purpose of flange 12 is to solder or otherwise fix it to the fluted 80 body 3 while the flange 13 has for its purpose to direct the heated air outwardly from the radiator instead of allowing it to go upwardly.

Having thus described my invention what 85 I claim as new is:

1. A radiator of the class described comprising a fluted body, a top having a plurality of apertures mounted on the body and including a pair of flanges extending from its 90 edges one of said flanges extended at right angles from the body of the top and the other flange extending at an obtuse angle therefrom, said right angularly extending

flange being in engagement with the fluted body.

2. A combined heating and humidifying water containing radiator comprising a body having its walls corrugated or fluted to provide an extended heating surface and having a perforated top and fitted at the bottom with a lengthwise extending internal heat-

ing pipe passing through the water and non-
communicating therewith.

10 In testimony whereof I affix my signature in presence of two witnesses.

LEONARD F. BURCHETT.
